CLAIM

We claim the ornamental design for a mobile two-door food cabinet, as shown and described.

DESCRIPTION

FIG. 1 is a perspective view of a mobile two-door food cabinet showing our new design;

FIG. 2 is a front elevation view thereof;

FIG. 3 is a right side elevation view thereof;

FIG. 4 is a left side elevation view thereof;

FIG. 5 is a top plan view thereof;

FIG. 6 is a rear elevation view thereof;

FIG. 7 is a bottom plan view thereof; and,

FIG. 8 is a bottom perspective view thereof.

Broken lines in the drawings are for the purpose of illustrating presently unclaimed portions of a mobile two-door food cabinet and form no part of the claimed design.

1 Claim, 7 Drawing Sheets(56)
